LIGHT FIXTURE

Carl E. Baldauf, Los Angeles, Calif., assignor to
Clarice Lienhard, Los Angeles, Calif.

Refiled for abandoned application Serial No.
93,441, July 30, 1936. This application July
22, 1938, Serial No. 220,796

3 Claims. (Cl. 240—78)

This invention relates to and has for an object thereof the provision of a light fixture wherein in a bowl, globe or reflector is secured in place in such manner as to comprise an effective moisture proof and dust proof enclosure for a light bulb and its socket. This application is a duplicate of, and is refiled for, abandoned application Serial Number 93,441, filed July 30, 1936.

Another object of the invention is to provide a light fixture which is constructed and arranged to greatly facilitate the installation thereof in a wall or ceiling or like support and to permit of a ready and easy changing of the bowl and light bulb whereby, after installation, bowls and bulbs of various sizes may be applied as desired.

A further object is to provide a novel and efficient means for sealing the fixture for preventing moisture and dust from entering the interior thereof.

20 An additional object is to provide a light fixture which may be readily and easily assembled and disassembled, which provides a novel socket structure and means for securing same in place; which includes an efficient means of detachably securing together a bowl supporting and adapter plate to an outlet box or condulet and also includes an efficacious means for clamping and holding the fixture to a wall or ceiling or other support.

30 With the above and other objects in view the invention subsists in the novel method and combination of parts hereinafter described, illustrated in the accompanying drawings, and set forth in the claims hereto appended, it being understood that various changes in form, proportion, size and minor details of construction within the scope of the claims may be resorted to without departing from the spirit or sacrificing any of the advantages of the invention.

40 In the drawing:

Figure 1 is a side elevation of the fixture of this invention as when installed and shown partly in section.

Figure 2 is a schematic view of the outlet box and light socket unit as when disassembled, parts being separated and shown in section.

Figure 3 is a fragmentary view of the fixture attaching, sealing and globe supporting means as when disassembled, the parts being separated and shown in section.

50 Figure 4 is a sectional view of the unit of Figure 2 as when assembled with a larger type of light bulb socket.

The present embodiment of the light fixture 55 of this invention, as seen in the accompanying

drawing, generally comprises an outlet box 1 having a threaded socket or extension 2, an adapter and fixture clamping plate 3, an attaching hub 4 formed integral with said plate and threadedly and removably engaged with said extension, a light bulb socket 5 held in place by and forming a seal between said hub and outlet box, a clamping and sealing ring 6 opposed to said plate and threaded on said hub, a globe or bowl 7, and a means 8 for detachably securing said bowl to said plate and for forming a seal there-between.

The outlet box is adapted to be set up on one side (the interior) of a wall or ceiling as indicated at A in Figure 1, and the wires, not shown, are connected with the socket 5 which is cemented in 15 a holder 9 having a flange 10. On opposite sides of this flange are gaskets 11 respectively engaged with a flange 12 on the outlet box and the upper or inner end of the hub 4. Thus when the hub is screwed up, it clamps the socket 5 in place so as to form a moisture and dustproof seal between the hub and outlet box. The outer shell 13 of the socket 5 is screwed up on the threaded body of the socket proper and a gasket 14 provides a moistureproof seal and non-chipping joint of the 25 porcelain parts of the socket.

The ring 6 is placed on the inner side of the wall so that when the hub is screwed in place it threads through said ring and thereby causes the ring to clamp the gasket 15 against the inner 30 side of the wall. Likewise, as the hub 4 is screwed into the outlet box, the plate 3 is forced against the wall as shown in Figure 1. With the fixture thus assembled, it will be seen that the light socket 5 lies partly in the outlet box and 35 partly in the hub in position to receive the light bulb screwed in place therein in the usual manner.

The means 8 for removably securing the bowl or globe 7 in place comprises, as here shown, a 40 ring 16 having an inwardly extending globe supporting flange 17, a gasket 18 between said flange and globe, a split, resilient ring 19 engaged in a groove 20 and holding the globe against the flange, an outwardly extending flange 21 removably secured to the plate 3 by fastenings 22, and a sealing gasket 23 between the plate 3 and flange 21.

It will now be seen that the fixture may be 50 readily assembled and installed and may be disassembled with equal facility.

It is important to note that the entire unit comprising the globe or bowl 7, means 8, plate 3 and hub 4, while assembled may be removed by 55

bodily turning the globe to unscrew the hub 4 from the threaded extension 2 of the outlet box.

This will facilitate changing the adapter plate 3 whereby to provide for larger or smaller light bulbs and bowls as desired.

However the bowl may in some instances, depending on the size of the light bulb, have to be removed from the plate 3 before unscrewing the hub 4 and this can be readily accomplished by 10 removing the fastenings 22.

It will be noted that all joints of the fixture are gasketed and arranged to provide effective moisture and dustproof seals.

It should also be noted that with this fixture 15 no fastening screws or the like are required to secure the bowl supporting plate in place. The fastening means therefor is not visible when the fixture is assembled whereby to improve the appearance of the fixture as a whole and provide 20 for an easier installation and removal thereof.

I claim:

1. In a light fixture, an outlet box adapted to be placed on one side of a wall or ceiling, a threaded extension on said box, a clamping and 25 adapter plate adapted to engage the other side of the wall or ceiling, a hub integral with said plate and threadedly engaged with said extension, a light socket held in place by and between said extension and hub and extending into the latter,

a bowl and means for securing said bowl to said plate and a clamping ring threaded on said hub and adapted to clamp against the wall or ceiling.

2. In a light fixture, an outlet box, a threaded extension on said box, a flange in said extension, 5 a clamping and adapter plate, means on said plate for securing a bowl in sealed engagement therewith, a hub formed integral with said plate and having threaded engagement with said extension, a light bulb socket in said hub, a holder 10 to which said socket is secured and which is clamped between the upper end of the hub and said flange and a clamping ring threaded on said hub and being opposed to said plate.

3. In a light fixture, an outlet box, a threaded 15 extension on said box, a flange in said extension, a clamping and adapter plate, means on said plate for securing a bowl in sealed engagement therewith, a hub formed integral with said plate and having threaded engagement with said extension, a light bulb socket in said hub, a holder 20 to which said socket is secured and which is clamped between the upper end of the hub and said flange and a clamping ring threaded on said hub and being opposed to said plate, said plate 25 and bowl therein being detachable as a unit upon unscrewing said hub from said extension.

CARL E. BALDAUF.
